CAP FOR EXHAUST PIPES AND THE LIKE

Sol R. Rubin, Los Angeles, Calif.

Application January 1, 1943, Serial No. 471,087

2 Claims. (Cl. 98—84)

1

My invention relates to a cap means for exhaust pipes, ventilating flues, or the like.

One of the principal objects of this invention is to provide a cap means of this class which will not allow a down-draft in the pipe, flue, or the like, on which it is affixed, irrespective of air or wind conditions on the outside of the cap or the building on which it is provided.

A further object of this invention is to provide a cap means of this class which will create a negative flow of air or up-draft in the pipe or flue on which it is applied, irrespective of such air or wind conditions.

Another object of this invention is to provide a cap means of this class which is particularly simple and economical of construction and which will not readily deteriorate.

With these and other objects in view, as will appear hereinafter, I have devised a cap means for exhaust pipes, and the like, which has certain novel features of construction, combination, and arrangement of parts and portions, as will be hereinafter described in detail and particularly set forth in the appended claims, reference being had to the accompanying characters of reference thereon, which form a part of this application, in which:

Fig. 1 is a fragmentary side elevation of an exhaust pipe or ventilating flue extending above the inclined roof of a building, and showing my exhaust cap, in a preferred form of construction, at the top of the exhaust pipe or ventilating flue, portions thereof being broken away and shown in section to facilitate the illustration;

Fig. 2 is a top view thereof, also showing certain portions thereof broken away and in section to facilitate the illustration; and,

Figs. 3, 4, 5, and 6 are diagrammatic side elevational views of the cap, showing by arrows different air conditions, or different directions of wind with respect to the cap, and showing the air exhausting capacities thereof under such different directions of the wind.

The exhaust pipe or ventilating flue 1 is of conventional construction and extends through and above the roof 2, which is shown in the drawing as inclined, the pipe or flue 1 being supported on and sealed with respect to the roof by the usual flashing member or cone 3.

My exhaust cap means is to be applied to the top of such exhaust pipe or flue. In this instance the exhaust cap means is provided with a separate supporting neck 10 which may telescope over the top and outside of the pipe 1. Around the upper end of the neck 10 is a skirt 11, the upper 55 shown in Figs. 1, 3, 4, 5, and 6, and these are indi-

2

end of the skirt extending above the upper end of the neck a distance slightly greater than the distance of the lower end of the skirt below the upper end of the neck. The cross-sectional area between the neck 10 and the skirt 11 may be substantially that of the cross-sectional area of the neck, but, as shown, is slightly less than the latter. The hood 12, which is of flat cone shape, may be approximately twice the diameter of the pipe or neck, and also extends considerably beyond the open upper end of the skirt. The circumferential area of the opening between the upper end of the skirt and the hood is substantially equal to or slightly greater than the cross-sectional area of the skirt, so that the exhaust of the air beyond the upper opening of the skirt will not be choked.

The neck 10, the skirt 11, and the hood 12 are all shown cylindrical or circular and are all arranged coaxially, and these elements are supported in such relation by a plurality of straps 13, the same strap securing all three elements together. Below the open end of the skirt is arranged a disc shaped baffle 14, the same being secured to the neck 10 by means of brackets 15. The baffle 14 is positioned such a distance below the lower end of the skirt 11 that the cross-sectional area between the skirt and the baffle is greater than the cross-sectional area between the neck and the skirt. The outer diameter of the baffle 14 is also greater than the diameter of the skirt, as shown. The positions of the baffle 14 below the skirt and the spacing of the latter outwardly from the neck is such that wind which passes upwardly from below the baffle in a vertical direction, or a relatively sharp angle to the vertical direction, will be deflected outwardly from such cap by the baffle. The spacing of the baffle below the skirt and the position of the upper end 40 of the neck above the lower end of the skirt is such that a horizontal wind, or wind which makes only a slight angle with such horizontal direction, will rather be split and the major portion will pass around the neck. The relation between the several elements is such that the lower end of the skirt 11 intersects or is positioned slightly below the line extending through or between the peripheral edge of the baffle and the top of the pipe, or so that the lower edge of the skirt is positioned 45 in such relation to the conical plane which is tangent to the peripheral edge of the baffle and the top of the neck, such plane being indicated by P in Fig. 1.

Different wind conditions or directions are

cated, respectively, by A, B, C, D, and E in these figures.

In Fig. 1 the wind, represented by the arrow designated A, is shown as directed horizontally from the side. The air will impinge against the pipe or neck 1 below the skirt and will be split and deflected to the opposite sides, and only a small part of the air will rise into the skirt. The air directed above the skirt will pass below the hood from one side of the skirt to the other. The latter air will cause an up-draft both in the pipe 1 and in the skirt.

The direction of the wind in Fig. 3 is designated by B, it being directed at an angle from the side and from above. The air will impinge against the top of the hood and will be deflected as indicated by B¹. The air directed toward the forward side or portion of the hood will be deflected downwardly toward the side of the cap, as indicated by B², and the principal portion will be directed downwardly past the baffle. A portion of the air will be directed over the top of the baffle, as indicated by B³, and will tend to draw air from the bottom of the skirt. The air passing downwardly beyond the edges of the hood, and also downwardly from the skirt, will tend to draw air from the top and bottom of the skirt, as indicated by B⁴ and B⁵, respectively. This will create an up-draft in the pipe or neck.

In Fig. 4, the wind, designated C, is shown as assuming a downward path directly against the top of the hood. The hood will cause such down-current to pass by the cap, shown by C¹, creating a vacuum primarily at the top of the skirt and perhaps a slight vacuum at the bottom of the skirt, as indicated by C² and C³, respectively. The rarefied condition of the air at both ends of the skirt will cause an up-draft in the pipe or neck. Heretofore exhaust caps have been made to prevent down-draft under the three aforementioned air or wind conditions. However, they have not all been efficient in providing the desired up-draft under such conditions. None of the exhaust caps now in use, however, have been efficient either to prevent down-draft or create up-draft in either of the two directional wind conditions presently to be described.

In Fig. 5 of the drawing, the direction of the wind, designated D, is at an angle from below. The principal portion of the air will assume a path toward the top of the skirt, as indicated by D¹, and the air will pass over the top of the skirt to the opposite side of the hood. Such passage of the air will cause a rarefied condition at the top of the skirt and produce an up-draft in the pipe or neck. Since the outer edge of the baffle extends beyond the skirt, any air passing between the baffle and the lower end of the skirt will be

split by the pipe or neck and tend to flow around the latter, as indicated by D², rather than pass upwardly into the skirt. A small portion of such air, however, may pass upwardly into the skirt and will cause a slight additional vacuum at the upper end of the pipe or neck and assist in the up-draft therein.

In Fig. 6 of the drawing, the wind is shown as passing directly upwardly along the outer side of the pipe. This condition may take place when the exhaust pipe or ventilating flue is located at the side of a steep pitched roof, or when the pipe is located near a parapet wall or in the corner of such walls. In this instance, the baffle will cause the wind to be diverted outwardly and assume a direction indicated by E¹. This will cause rarefied conditions at the upper and lower ends of the skirt and result in an updraft in the pipe or neck, as indicated, respectively, by E² and E³.

Though I have shown and described a particular construction, combination, and arrangement of parts and portions and have described particular theories of action in relation to different wind conditions, I do not wish to be limited to the same, but desire to include in the scope of my invention the construction, combination, and arrangement substantially as set forth in the appended claims.

I claim:

1. In an exhaust cap of the class described, a supporting tubular neck for the top of an exhaust pipe, a co-axial skirt surrounding and spaced outwardly therefrom with its upper and lower ends positioned respectively above and below the opening at the upper end of the neck, a hood positioned and spaced above the upper end of the skirt, a baffle spaced below the lower end of the skirt and extending laterally from the neck, the lower edge of the skirt lying substantially within the conical surface extending between the outer edge of the baffle and the upper edge of the neck, and means for securing the neck, skirt, and hood in said spaced relation.

2. In an exhaust cap of the class described, a supporting tubular neck for the top of an exhaust pipe, a coaxial skirt surrounding and spaced outwardly therefrom with its upper and lower ends positioned respectively above and below the opening at the upper end of the neck, a hood positioned and spaced above the upper end of the skirt, a baffle spaced below the lower end of the skirt and extending laterally from the neck, the lower edge of the skirt lying substantially within the conical surface extending between the outer edge of the baffle and the upper edge of the neck, and means for securing the neck, skirt, and hood in said spaced relation.

SOL R. RUBIN.
